HAMILTON E. SMITH, OF NEW YORK, N. Y.

Letters Patent No. 96,358, dated November 2, 1869.

IMPROVEMENT IN PERFORATED WEARING-APPAREL.

The Schedule referred to in these Letters Patent and making part of the same

To all whom it may concern.

Be it known that I, HAMILTON E. SMITH, of New York city, in the county and State of New York, have invented a new and useful Improvement in Skin and other Garments of Close Texture; and I do hereby declare that the following is a full, clear, and exact description thereof, which will enable others skilled in the art to make and use the same, reference being had to the accompanying drawing forming part of this specification.

The invention relates to and consists in an improved inner garment for persons afflicted with rheumatism or kindred diseases, or those whose delicacy of constitution necessitates some effective protection against fluctuations of climate or temperature.

The ordinary flannel or other woolen or cotton material, which serve to exclude cold by the quantity of air entangled in their interstices, and of their consequent want of conducting-capacity, are, on the other hand, extremely injurious to the general health, by clogging the ducts and pores of the skin.

The exhalations, which are poured in a continuous stream through the millions of conduits which empty on the surface of the skin, accumulate in a short time to such an extent as to almost prevent the further exit of perspiration and other excretory matter. Hence, in guarding weak constitutions against one evil, the vital organs, which perform the most important functions, become irreparably injured, and the remedy is found, too late, to be worse than the disease.

The object of my invention is to meet this great difficulty, and to provide under-garments which will combine all the advantages of non-conducting material with means for rapidly eliminating all the excretory

matter as fast as it exudes from the skin. (Wool, swan's-down, and other like substances are not suited to the object in view.) In order to accomplish this end, I take buck or other skins, partially tanned. At suitable intervals, I punch, or, in some other way, perforate the same, thereby providing numerous outlets for the rapid and certain escape of all noxious exhalations.

An inner garment thus prepared provides a sure and effectual preventive against the evils arising from sudden and violent changes in the weather; and is beneficial and preservative of health in all cases, even where robust health is found.

In the drawing is shown an exemplification of my invention, wherein is exhibited a garment which covers the entire surface of the body, and, while it interferes at no time with the exact, full, and regular performance of their functions by all the bodily organs, operates as a complete protection for the purpose above described.

Having fully described the manner in which my garment is made,

What I claim as of my own invention, and desire to secure by Letters Patent, is—

As a new article of manufacture, the inner garment above described, made of buck or partially-tanned skins, perforated, as and for the purpose specified.

The above specification of my invention signed by me, this 1st day of June, 1869.

HAMILTON E. SMITH.
